Ohio, assignors to The Midland Steel Products
Company, Cleveland, Ohio, a corporation of
Ohio

Application August 4, 1936, Serial No. 94,212

7 Claims. (Cl. 60—52)

This invention relates to new and useful improvements in riveters and more particularly to improvements in hydraulic riveting machines.

An object of the invention is to provide a portable riveter which is strong, durable and inexpensive of construction, and which is under the perfect control of the operator by manipulating only a single valve in the handle of the riveter.

Another object of the invention is to provide a portable riveter which is relatively small in size and contains intensifying means to develop relatively high pressures.

A further object of the invention is to provide a riveter wherein the intensifying means and ram means are retracted at relatively high speed compared to the advancement thereof toward a work piece.

Another object of the invention is to provide liquid distributing passages within the riveter housing resulting in a more compact apparatus and reduction in the number of external high pressure conduits with less liability of leakage and damage by bursting of the pipes.

Other objects and advantages will become apparent during the course of the following description.

In the accompanying drawings forming a part of the description and wherein like numerals are employed to designate like parts throughout the several views,

Fig. 1 is a broken elevational view of a hydraulic riveter and the adjuncts to suspend the riveter and to supply hydraulic pressure thereto,

Fig. 2 is a sectional view partly in elevation taken along the line 2—2 of Fig. 4,

Fig. 3 is a sectional view taken along the line 3—3 of Fig. 2,

Fig. 4 is a sectional view taken along the line 4—4 of Fig. 2, and

Fig. 5 is a sectional view taken along the lines 5—5 of Fig. 2.

The portable hydraulic riveter herein disclosed comprises a housing 10 provided with a longitudinally extending fluid cylinder 11 divided by an annular block 12 to form a pressure cylinder 13 and a ram cylinder 14, the latter having a reduced end 15 embraced by an arm 16 of a riveting yoke 17 which is rigidly secured to the housing 10 by means of a nut 18 threaded on to the reduced end 15 of the ram cylinder 14 to draw the riveting yoke 17 against the shoulder 19 of the housing. The other arm 20 of the yoke 17 is provided with a die 21 faced to accommodate a rivet not shown.

Reciprocally mounted in the ram cylinder 14

is a ram construction 25 having a ram piston 26 and a ram 27 of smaller diameter which extends through the reduced end 15 and is provided at its free end with a die 28 for cooperation with the riveting die 21 to accommodate a rivet therebetween. The piston 26 is provided with a sealing ring 30 and the ram 27 with sealing rings 31 to prevent passage of liquid from one side to the other thereof. Additional sealing means are disposed at the upper end of the ram piston 26 and comprise an annular L-shaped yieldable packing 43 held in position by a nut 32 threaded on the piston 26. The packing has its free end 33 so disposed as to be forced by liquid into sealing engagement with the inner surface of the ram cylinder 14. A ram retracting chamber 34 is provided between the ram 27 and the ram cylinder 14 and communicates with a source of fluid in a manner hereinafter described to retract the ram device 25.

The pressure cylinder 13 is closed by a cap 35 secured to the housing 10 by a nut 36 and has a transverse passage 39 and a central port 37 communicating with a flexible conduit 38 leading to a source of fluid pressure. The opposite ends 25 of the transverse passage 39 communicate through ports 40 and 41 with a pressure chamber 42 between the cap 35 and an intensifying device 45 in the pressure cylinder 13. Disposed in the transverse passage 39 is a ball check valve 46 30 limited in movement in one direction by a pin 47 and engageable with a valve seat 48 to interrupt flow of fluid through the port 40 and thus to the pressure chamber 42.

The pressure intensifying device 45 comprises 35 an intensifying piston 50 fitted in the cylinder 13 and an intensifying ram 51 of smaller diameter which is slidably received in a bore 52 in the annular block 12. Sealing means are disposed at the upper end of the piston 50 and include an 40 annular L-shaped yieldable packing 55 retained by a nut 56 threaded on the piston 50 and has its free end 57 so arranged as to be forced by liquid in the chamber 42 into sealing engagement with the cylinder 13. In the intensifying piston 50 is 45 a recess 53 for the purpose of increasing the volume of the pressure chamber 42 and for reducing the weight of the piston 50. The intensifying ram 51 forms with the cylinder 13 an annular 50 retracting chamber 60 which communicates with a source of fluid pressure to retract the intensifying device 45.

An intensifying chamber 62 is formed between the intensifying ram 51, the annular block 12 and 55

the ram piston 26 which is also provided with a recess 61 forming part of the chamber 62.

The annular block 12 is held in position by means of a sleeve 29 and the cap 35, and acts as a distributing device to distribute fluid to the retracting fluid chambers 34 and 60 and to the intensifying chamber 62 and comprises a plurality of vertical bores 64 which are exposed to the retracting chamber 60 and to the transverse ports 65 leading to an annular recess 66 exposed to ports 67 disposed in the wall of the housing 10, which ports lead to a pair of spaced passages 68 formed in the wall of the housing 10 and extending to ports 69 leading to the ram retracting fluid chamber 34. The annular recess 66 also communicates with a source of fluid pressure by means of the port 71 accommodating one end of a flexible conduit 70 connected to the fluid pressure source, whereby fluid under pressure is supplied to the intensifying ram retracting chamber 60 and the riveting ram retracting chamber 34. The distributing block 12 is provided with another annular recess 75 which communicates with ports 76 exposed to the intensifying chamber 62, and also communicates with a pair of ports 77 terminating in a pair of passages 78 in the wall of the housing 10 which communicate with a recess 79 in the cap 35 at the end of the transverse passage 39 which in turn is connected to the source of fluid pressure through the conduit 38. This recess 79 is larger than port 41 whereby fluid first passes to chamber 62 and builds up pressure before a sufficient pressure builds up in chamber 42 to cause the ram 51 to move sufficiently to close ports 76.

The riveter is suspended over pulleys 80 by means of a cable 81 and a counterweight 82 whereby the riveter may be easily manipulated into any desired position by means of the handle 83. Disposed in the handle 83 is a conventional electric switch not shown, operated by the switch button 84 connected by an electric conductor 90 to a solenoid 85 which operates a valve 86 to control the flow of liquid subjected to pressure by a pump 87.

The control valve 86 comprises a housing 95 provided with a longitudinally extending bore 96 communicating with a by-pass 97 and with a port 98 connected to the flexible conduit 70, a port 99 connected to the flexible conduit 38, a port 100 connected to a conduit 101 leading to the pump 87 and a port 102 connected to a conduit 103 leading to a reservoir 104 connected by means of a conduit 105 to the pump 87. The flow of fluid through these ports is controlled by a valve 106 disposed in the bore 96 and is connected to a core 107 which is normally urged to the release position shown in Fig. 1 by a spring 108 in the valve housing 95.

When the hydraulic press is idle, the switch button 84 is in off position and the valve 106 is in the position shown in Fig. 1, whereby the pump 87 delivers fluid under pressure through the conduit 101, bore 96, port 98 and flexible conduit 70 to the annular recess 66 in the distributing block 12, from which it is distributed to the passages 68 and ports 69 into the chamber 34 to support the ram means 25 in retracted position shown in Fig. 2, and liquid is also distributed from the annular recess 66 through the vertical bores 64 into the chamber 60 to support the intensifying means 45 in retracted position shown in Fig. 2.

To start the riveter, the operator presses the switch button 84 to energize the solenoid 85 which

expels the core 107 to move the valve 106 to the right as viewed in Fig. 1, whereby the pump 87 delivers fluid under pressure through the conduit 101, bore 96, port 98 and flexible conduit 70 into the transverse passage 39 from which liquid passes through the passages 78, ports 77, annular recess 75 and bores 76 into the intensifying chamber 62. The liquid entering the intensifying chamber 62 protracts the ram means 25 and as this happens the volume of the intensifying chamber 62 is increased. After the ram means 25 is protracted and meets resistance of a rivet, pressure building up in passage 39 is directed through the smaller port 41 into the pressure chamber 42 and moves the intensifying ram 51 into the bore 52 of the distributing block 12 to close the lateral ports 76, thereby preventing the escape and entrance of fluid in the intensifying chamber 62. Upon continued protraction of the intensifying ram 51 the latter exerts pressure upon the liquid confined in the intensifying chamber 62 and causes the ram 27 to exert high pressure upon the rivet placed between the rivet dies 28 and 21. As the intensifying ram 51 and riveting ram 27 are advanced the pressure in the chambers 60 and 34 is relieved through the annular recess 66, flexible conduit 70, port 98, by-pass 97, port 102, and conduit 103 to the reservoir 104.

It will be understood that the final pressure transmitted to the riveting ram 27 is extremely high compared to the initial pressure. This is due to the fact that prior to closing the ports 76 the liquid in the intensifying chamber 62 is subjected only to pump pressure, but upon closure of the ports 76 by the intensifying ram 51, the pressure developed in the intensifying chamber 62 will be greatly increased, because the effective area of the intensifying piston 50 is far greater than the area of the intensifying ram 51 in the chamber 62, thus causing the riveting ram 27 to impart pressures to the work which are considerably higher than that developed by the pump.

When the ram 27 meets resistance of the work, pressure builds up in chamber 62 and also in 42 moving intensifying piston 51 downwardly until the port 76 is cut off. The speed of the ram 27 will now slow down because less fluid is displaced by the intensifying ram 51 in chamber 62 and enters chamber 42, for a definite movement of the intensifying piston 50. The pressure in chamber 42 now being high and in chamber 62 still higher due to the differential areas of pistons 50 and 51, the speed of the ram 27 is reduced while pressure thereon is intensified.

In order to retract the riveting ram 27 the operator releases the switch button 84 which de-energizes the solenoid 85 to move the valve 106 to off position, whereby the pump 87 delivers liquid under pressure through conduit 101, port 98 and the flexible conduit 70 into the annular recess 66 from which it is distributed through the ports 67, passages 68 and ports 69 to the chamber 34 to thus move the ram piston 26 upwardly. At the same time pressure builds up in the annular recess 66, the ports 64 and chamber 60 to retract the intensifying piston 50. Upon retraction of the intensifying means and riveting means the pressure in the intensifying chamber 62 is relieved through the passages 78, transverse bore 39 and the flexible conduit 38 to the reservoir 104 and the pressure in the pressure chamber 42 is relieved through both of the ports 40 and 41, and the passage 39 and conduit 38. The speed 75

of retraction of the intensifying means and riveting means will be greater than the speed of advancement since both of the ports 40 and 41 are open during retraction and chambers 34 and 56 are of less volume than chambers 42 and 62.

It will be understood that various changes in the construction and arrangement of parts may be resorted to without departing from the scope of the appended claims.

10 We claim:

1. In a fluid cylinder, ram means having a ram piston in said cylinder, and a ram, a retracting fluid chamber below said piston communicable with a source of fluid for retraction of said ram means, intensifying means having an intensifying piston in said cylinder and an intensifying ram, of less area than said ram piston and intensifying piston and located above the ram piston a fluid retracting chamber below the intensifying piston communicable with said source of fluid for retraction of said intensifying means, ported means defining an intensifying fluid chamber between said intensifying ram and said ram piston and communicable with said source of fluid to advance said ram means, a fluid pressure chamber above the intensifying piston communicable with said source of fluid to advance said intensifying ram into said intensifying fluid chamber to interrupt communication of the latter with said source of fluid pressure and confine the fluid therein to exert pressure upon the fluid within said intensifying chamber to advance said ram means, means for delivering fluid into said pressure and intensifying chambers to advance said ram means and intensifying means, means for delivering fluid to said retracting fluid chambers to retract said ram means and said intensifying means, said retracting chambers being of less capacity than the intensifying and pressure chambers, means including a check valve to allow a more rapid flow from said pressure chamber upon retraction of said intensifying means than upon the advancement of said intensifying means, and valve control means for directing the flow of fluid from said pressure source to effect advance and retraction of said ram means and intensifying means.

2. In a fluid cylinder, ram means in said cylinder, intensifying means of restricted area in said cylinder and spaced from said ram means to define an intensifying fluid chamber, a fluid pressure protracting chamber adjacent said intensifying means communicating with a source of fluid pressure to advance said intensifying means and said ram means, a fluid retracting chamber for retraction of said intensifying means, and means including a restricted passageway communicating with said pressure protracting chamber, a port communicating with said chamber and a check valve at said port to allow more rapid flow of fluid from said pressure protracting chamber upon retraction of said intensifying means than upon advancement of said intensifying means, to thereby effect more rapid retraction of said ram means than advancement of the same.

3. In a fluid cylinder, ram means having a ram piston in said cylinder and a ram, a first retracting chamber, intensifying means having an intensifying piston and an intensifying ram, smaller than its intensifying piston and the ram piston, a second retracting chamber, means defining an intensifying fluid chamber between said intensifying ram and said ram piston, said means having a fluid chamber port exposed to

said second retracting chamber and having an intensifying port exposed to said intensifying chamber, the wall of said cylinder having a passage for connecting said fluid chamber port and said first retracting chamber to a source of fluid pressure for retraction of said ram means and said intensifying means, said wall of said cylinder having a second passage for connecting said intensifying chamber port with a source of fluid pressure to advance said ram means, and a pressure chamber adjacent said intensifying piston communicating with said source of fluid pressure for advancing said intensifying means.

4. In a fluid cylinder, ram means having a ram piston in said cylinder and a ram, a first retracting chamber, intensifying means having an intensifying piston and an intensifying ram, said intensifying ram being smaller in area than said ram piston and said intensifying piston, a second retracting chamber, means defining an intensifying fluid chamber between said intensifying ram and said ram piston, said means having a fluid chamber port exposed to said second retracting chamber and having an intensifying port exposed to said intensifying chamber, the wall of said cylinder having a passage for connecting said fluid chamber port and said first retracting chamber to a source of fluid pressure for retraction of said ram means and said intensifying means, the wall of said cylinder having a second passage for connecting said intensifying chamber port with a source of fluid pressure to advance said ram means, a pressure chamber above said intensifying piston communicating with said source of fluid pressure for advancing said intensifying means, and means in the wall of said fluid cylinder communicating with said pressure chamber and including a check valve to allow more rapid flow of fluid from said pressure chamber upon retraction of said intensifying means than upon advancement of said intensifying means.

5. In a fluid cylinder, a dividing block therein dividing the cylinder in a pair of compartments and having a bore smaller than said cylinder and ports communicating with the compartments, said block having a control port communicating with said bore, a ram piston mounted in the lower compartment and defining a retraction chamber beneath the same and a protraction chamber above the same communicating with said bore of the block to provide an intensifying chamber, an intensifying piston in the upper compartment dividing the same into a lower retraction chamber and an upper protraction chamber and having a reduced ram operating in said bore of said block and adapted to cut off communication of said control port with said bore during downstroke of the intensifying ram, the wall of said cylinder having a passage communicating with said port, a cap for the cylinder having a control chamber connected with a source of pressure and communicating at one end with said passage in the cylinder wall to convey pressure to the intensifying chamber, said cap having a port of smaller area than said passage connecting the cap chamber to the protracting chamber above the intensifying piston to convey fluid under pressure thereto after pressure has been initiated in said intensifying chamber, and a valve controlled passage from said cap chamber to said protracting chamber normally closed by predominating pressure in the cap chamber and opened to vent the protracting chamber above the

intensifying piston upon creation of predominating pressure therein.

6. In a fluid cylinder, a member therein dividing the cylinder into upper and lower compartments having a ported reduced axial bore, a first piston in said lower compartment forming a retracting chamber therebeneath, a second piston in the upper compartment having an intensifying ram of smaller diameter than either of said pistons operating in said reduced bore, a retracting chamber between the second piston and said dividing member, a protraction chamber above said second piston, and a conduit between said protracting chamber and said ported reduced bore to supply the latter with fluid until cut off by protraction of said intensifying ram.

7. In a fluid cylinder, a member therein dividing the cylinder into upper and lower compart-

ments having a ported reduced axial bore, a first piston in said lower compartment forming a retracting chamber therebeneath, a second piston in the upper compartment having an intensifying ram of smaller diameter than either of said pistons operating in said reduced bore, a retracting chamber between said second piston and said dividing member, a protraction chamber above said second piston, and a conduit between said protracting chamber, said ported reduced bore to supply the latter with fluid until cut off by protraction of said intensifying ram, and said protracting chamber having means to cause a more rapid flow from the space above the second piston than toward said space.

GEORGE H. KESSLER.
